[57] CLAIM

The ornamental design for an automobile seat cover, as shown and described.

DESCRIPTION

FIG. 1 is a rear perspective view of the design for an

automobile bucket seat cover, shown in place upon an automobile bucket seat, no claim for which said bucket seat is being made;

FIG. 2 is a front view thereof;

FIG. 3 is a right side elevational view, the left side being a mirror image thereof;

FIG. 4 is a top plan view thereof;

FIG. 5 is a rear view thereof;

FIG. 6 is a bottom view thereof;

FIG. 7 is a rear perspective view of an alternate embodiment for the automobile bucket seat cover, shown in place upon an automobile bucket seat, no claim for which said bucket seat is being made;

FIG. 8 is a front view of the alternate embodiment thereof;

FIG. 9 is a right side view of the alternate embodiment, the right side being a mirror image thereof;

FIG. 10 is a top plan view of the alternate embodiment thereof;

FIG. 11 is a rear view of the alternate embodiment thereof; and,

FIG. 12 is a bottom view of the alternate embodiment thereof.
